CONTROL DEVICE

Lewis R. Koller and Ralph P. Johnson, Schenectady, N. Y., assignors to General Electric Company, a corporation of New York

Application March 26, 1938, Serial No. 198,339

5 Claims. (Cl. 250—27)

The present invention relates to an improved control device, which has a definite lock-out characteristic; that is, which acts positively in such a way as to prevent "chattering".

5 The features of novelty which we desire to protect herein will be pointed out with particularity in the appended claims. The invention itself, together with further objects and advantages thereof, may best be understood by the following 10 description taken in connection with the drawing, in which Fig. 1 is a schematic representation useful in explaining the principle of operation of the invention; Fig. 2 shows diagrammatically one practical embodiment of the invention; 15 Fig. 3 illustrates graphically the operating characteristics of the device of Fig. 2; Fig. 4 shows an alternative embodiment of the invention, and Fig. 5 illustrates the operating characteristics of the device of Fig. 4.

20 The invention makes use of secondary emission, that is to say, the emission of electrons from an electrode surface in response to the impingement of primary electrons on such surface. The manner in which this phenomenon is utilized is indicated in Fig. 1.

25 In the arrangement shown, there is provided a cathode C which acts as a source of primary electrons; a secondary emission electrode P adapted to receive primary electrons and to generate secondary electrons as a result of the 30 primary electron flow thereto, and an anode A adapted to receive secondary electrons emitted from the surface of the electrode P. It is assumed that the anode A is so constructed and arranged that it collects few, if any, of the primary electrons. A battery B connected between the cathode and anode serves to maintain the latter at a positive potential with respect to the former. The connection between the cathode and the secondary emission electrode P includes 35 a high resistance R.

40 The device may be brought to a conductive state by instantaneously applying positive potential to the electrode P (from a source not shown). Thereafter, the electrode simultaneously receives a stream of primary electrons I_p from the cathode and emits a stream of secondary electrons I_s which proceeds to the anode A. Consequently, the current which flows in the 45 external circuit connected to the electrode P has a value represented by the difference quantity $I_s - I_p$. This current serves to fix the potential of the electrode P by virtue of the voltage drop which it creates across the resistance R. As long 50 as the value I_s is greater than the value I_p this

potential will be positive with respect to the cathode.

5 Assume, however, that some means is provided for varying the primary electron current from the cathode C as, for example, by varying the emission of the cathode C. If this means is permitted to reduce the value of the primary current I_p , the secondary current I_s would necessarily be proportionately decreased. Their difference also will be diminished and the potential of the electrode P will drop, thus lessening still further the number of secondary electrons emitted by it. (It will be observed that the electrode potential is thus predominantly a function of the primary electron current.) When a condition is reached at which the second electron current is precisely equal to the primary electron current, it is clear that the current flowing through the resistance R will be zero and the potential of the electrode P will be equal to that 10 of the cathode C. Under these conditions the latter electrode can receive no primary electrons since such electrons will be repulsed by its electrostatic field, and the tube will cease to become conductive (assuming always that the 15 anode A cannot be reached by primary electrons alone). Furthermore, the tube cannot be reenergized by merely increasing the potential of the anode A, or by raising the emissivity of the cathode C, since neither of these steps will be 20 effective to raise the potential of the secondary emission electrode P to a value at which it can receive electrons. The device described therefore has an inherent lock-out characteristic in 25 that it tends to become completely non-conductive at a certain critical value of the primary current. This value is adjustable by regulation of the value of the resistance R.

30 A practical application of the invention is illustrated in the more complete circuit of Fig. 2 in which there is shown a cathode 10 of light-sensitive character, that is, variable in emission in accordance with the intensity of light impinging on its surface. Opposite this electrode and in cooperative relation therewith there is 35 provided a secondary emission electrode 11 corresponding in function to the element P described in connection with Fig. 1. From a constructional standpoint this latter electrode need have no unusual characteristics since most electrode surfaces are adapted to emit secondary electrons to a degree sufficient for the purposes of the present invention. It may comprise, for example, a metal plate constituted of nickel, or the like.

Interposed between the cathode 10 and the electrode 11 there is provided a grid-like anode 13. This may receive some primary electrons but is intended to be energized primarily by secondary electrons which are emitted by the electrode 11 in response to the impingement thereon of primary electrons from the cathode. This anode is maintained at positive potential with respect to the cathode by means of a battery 14 and is connected to a utilization circuit comprising a load device 15 which is to be energized by current flowing from the anode. This device may comprise, for example, a relay adapted to control any type of energy-translating apparatus such, for example, as a motor, a lamp circuit, or a heating system.

Between the cathode 10 and the anode 13 there is provided a space charge grid 17 having a function which will shortly be described. This 20 may be connected to the secondary emission electrode 11 either directly, as shown, or through the intermediation of a battery adapted to maintain a desired biasing potential on the grid. A circuit including a resistance 18, which has a 25 value preferably, but not necessarily, on the order of 10^4 to 10^6 ohms, serves to connect the cathode to the grid 17 and to the electrode 11.

As previously stated, the current received by the anode 13 is a function of the primary current 30 impinging on the secondary emission electrode 11. In the arrangement illustrated, this primary current is caused to be variable in response to a controlling influence by the provision of a system including a lens 20 for focusing on the surface 35 of the cathode 10 a light beam whose intensity tends to approach a predetermined critical value. The source of the light beam may be chosen with relation to the element desired to be controlled. That is, for example, if the device is 40 to control a street lighting circuit, the cathode 10 may be exposed to a source of daylight so as to permit energization of the lighting circuit in response to decrease of daylight intensity below a predetermined level.

45 The value of the resistance 18 is so selected that at a predetermined desired value of primary electron current, the potential of the secondary emission electrode 11 will become equal to that of the cathode. As soon as this occurs the space 50 charge grid 17, which also attains the potential of the cathode, serves to prevent any further flow of primary electron current. Thus, it exerts a blocking action so that the supply of current to the utilization circuit is cut off.

55 As previously explained in connection with Fig. 1, a device of this kind cannot be made again conductive simply by increasing the emission of the cathode 10. Consequently, there is no tendency for the control to "chatter" or "hunt", if 60 the controlling influence fluctuates about its critical value. In order to reenergize the load device when such reenergization becomes desirable, one may impress on the secondary electrode 11 a potential above that of the cathode 10. This may 65 be accomplished, for example, by means of a switch 22 for instantaneously connecting the electrode to the positive terminal of the battery 14. After conductivity is established the device may again be rendered responsive to the control 70 influence by opening the switch 22.

The characteristic of a device such as that just described is illustrated in Fig. 3 wherein the curve E represents the variation of current to the anode 13 with changes in cathode emission.

75 It will be noted that the anode current decreases

relatively slowly until a critical point x is reached at which it drops abruptly to zero. This point corresponds to the value of the cathode emission at which the potential of the secondary emission electrode 11 becomes equal to that of the cathode. 5

The arrangement of Fig. 4 differs from that just described mainly in respect to the means provided for controlling the primary electron current. In this case the cathode is represented as comprising a filament 24 connecting with a battery 25 which supplies heating current to the filament. The filament is assumed to have substantially constant emission.

10 Spaced from the cathode there are provided a secondary emission electrode 27, a grid-like anode 28 and a space charge grid 29. These elements correspond in essential particulars to the similar elements described in Fig. 4. A battery 31 in series with a load device 32 is connected between the cathode 24 and the anode 28. A resistance 33 serves to fix the potential of the electrodes 27 and 29 in the manner previously explained.

15 Between the cathode 24 and the space charge grid 29 there is provided a control grid 35 which acts to regulate the flow of primary electrons from the cathode 24. This grid may be biased to a suitable potential by means of a battery 36 and is rendered responsive to a control influence by means of a control device connected in circuit with the grid as indicated at 37. The element 37 may comprise any known type of device 20 for varying the potential of the grid 35 in accordance with variations in an electrical or physical condition such as the condition of an electrical circuit or the condition of a heating device or 30 the like.

25 The operating characteristic of a device such as that shown in Fig. 4 is illustrated in Fig. 5 in which curve F represents the variations in current to the anode 28 with changes in the potential applied to the control grid 35. The dotted reference line depending downwardly from point y of curve F indicates a cut-off action of the device of Fig. 4 occurring at a negative control voltage corresponding to the value y. This is 40 the characteristic which might be obtained with a given resistance R₁. The cut-off point may be shifted, for example to a point Z, by employing a different and higher resistance R₂ between the cathode 24 and the secondary emission electrode 50 27. It will be understood that the control grid voltage is measured from the zero axis at the right of the representation of Fig. 5 and increases in negative magnitude as one proceeds to the left. 55

The device may be restarted after cut-off action by closing the normally open switch 39 so as to apply positive potential to the electrodes 27 and 29.

60 The devices which we have described are unusual in their rapidity of response. Particular devices which we have tested have proven to be capable of lock-out action in less than one micro second after the application of a favorable controlling potential. Furthermore, the rapidity of response can be varied by shunting by a condenser the resistance which connects the cathode to the secondary emission electrode. 65

65 While we have described our invention primarily in its operation as a control device it 70 will be understood that it is capable of other applications where a discharge device having an extremely sharp cut-off characteristic is desired. We aim in the appended claims to cover all equivalent modifications and applications which come 75

within the true spirit and scope of the foregoing disclosure.

What we claim as new and desire to secure by Letters Patent of the United States, is:

5. 1. In combination, a source of primary electrons, an electrode emitting secondary electrons only in response to the flow thereto of primary electrons from said source, an anode arranged to receive current only upon the occurrence of 5 secondary emission from the said electrode, a utilization circuit connected to said anode and energized by the current received thereby, means for varying the primary electron current, the said means being responsive to a controlling influence 10 which tends to approach a predetermined critical value, and means for causing the abrupt deenergization of the utilization circuit upon the attainment of the said predetermined critical value of the controlling influence, said last named 15 means including an impedance connection between said electrode and said source for making their potential difference predominantly a function of the primary electron current flowing between them, and means dependent on said potential difference for completely blocking the flow 20 of primary electrons upon the attainment of the said predetermined critical value of the controlling influence.
2. In combination, an electron emissive cathode, an electrode for emitting secondary electrons in response to the impingement thereon of primary electrons from said cathode, a grid interposed between the cathode and the secondary emission electrode and electrically connected to 25 the latter, a grid-like anode between the grid and the secondary emission electrode for receiving secondary electrons from the latter, a load device connected in circuit with the anode, means for varying the primary electron current, the said 30 means being responsive to a controlling influence which tends to approach a predetermined critical value, and means including a resistance connecting the cathode to the grid and the secondary emission electrode for making the potential level 35 of the latter elements predominantly a function of the primary electron current, the resistance being such that upon the attainment of the said predetermined value of the controlling influence the potential of the grid becomes effective completely to block the flow of primary electrons and thus to prevent the further supply of current to the load device.
4. A control device comprising a cathode having its emissivity variable in accordance with the intensity of the light to which it is exposed, an electrode for emitting secondary electrons in response to the impingement thereon of primary electrons from said cathode, a grid interposed between the cathode and the secondary emission electrode and electrically connected to the latter, a grid-like anode between the grid and the secondary emission electrode for receiving secondary electrons from the latter, a load device connected in circuit with the anode, and means including a resistance connecting the cathode to the grid and the secondary emission electrode for making their potential level predominantly a function of the primary electron current, the resistance being such that for a predetermined light exposure of 40 the cathode the potential of the grid becomes effective completely to block the flow of primary electrons and thus to prevent the further supply of current to the load device.
5. In combination, an electron emissive cathode, an electrode for emitting secondary electrons in response to impingement thereon of primary electrons from said cathode, a space-charge grid interposed between the cathode and the secondary emission electrode and electrically connected to the latter, a grid-like anode between the grid and the secondary emission electrode for receiving secondary electrons from the latter, a load device connected in circuit with the anode, a control grid between the cathode and the space charge grid, the said control grid having its potential variable in response to a controlling influence which tends to approach a predetermined critical value so as to regulate the flow of primary electron current from the cathode, and means including a resistance connecting the cathode to the space charge grid and the secondary emission electrode for making their potential predominantly a function of the primary electron current, the resistance being such that upon the attainment of the said predetermined value of the said controlling influence the space charge grid becomes effective completely to block the flow of primary electrons and thus to prevent the further supply of current to the load device. 45
3. In combination, an electron emissive cathode, an electrode for emitting secondary electrons in response to the impingement thereon of primary electrons from said cathode, a grid interposed between the cathode and the secondary emission electrode and electrically connected to the latter, a grid-like anode between the grid and the secondary emission electrode for receiving secondary electrons from the latter, a load device connected in circuit with the anode, means for varying the emission of the cathode, the said 50
